COMBINATION CLOTHES AND DUST CHUTE

Hugo F. Koran, St. Paul, Minn.

Application April 17, 1935, Serial No. 16,777

4 Claims. (Cl. 193—34)

An object of my invention is to provide an improved form of clothes chute leading from an upstairs room into the basement, and in combination with the same means permitting the sweepings from the room being afforded a passageway to the basement, and also means for storage.

This and other features of my invention will be more particularly set forth in the following description and the accompanying drawing, wherein:

Figure 1 is a view in front elevation of my improved construction.

Figure 2 is a view on the line 2—2 of Figure 1; and

Figure 3 is a sectional view corresponding to Figure 2, of a slightly modified construction.

Referring to the drawing in detail, and particularly to the constructions shown in Figures 1 and 2, I provide a boxing or framework consisting of front and rear walls 2 and 3 and top and bottom walls 4 and 5. This boxing or framework is ordinarily positioned in the wall between two rooms, such wall being indicated by the dotted lines 6 in Figure 2. The boxing is interiorly divided vertically by a wall 7 to form two passageways 8 and 9, one for clothes and one for floor sweepings, as hereinafter particularly pointed out.

In order to permit clothes to be placed into the chute 8 from both sides, I provide a door 10 in the front wall, a door 11 in the rear wall, and a door 12 supported above the partition wall 7. The boxing above the doors 11 and 12, as shown in Figure 2, extends upwardly some distance above said doors to form a compartment 13 in which may be supported shelves 14 and may be large enough to form a receptacle for articles, such as a broom 15.

A door 16 may also be provided in the rear wall above the door 11 to form an inlet to the shelves 14.

As it will be apparent, therefore, from one room the opening formed by the door 11 will be used to drop clothes into the chute, and from the other room the opening of the doors 10 and 12 will permit clothes to be passed into the chute.

The bottom wall 17 of the compartment 13 above the passageway 9 joins the front wall of the boxing with the central wall 7 to form the top of the passageway 9, a door 18 being hung in an opening in the front wall of the framework at the upper end of the passageway 9. The bottom of the door opening for the door 18 will be at a level with the floor line 19 so that the

floor sweepings may be swept through the door opening of the door 18 into the passageway 9 and dropped into a suitable receptacle 20 positioned in the bottom of the chute. This receptacle, as shown in Figure 2, and specifically illustrated in dotted lines, is removable so that the deposit of dirt may be removed from the chute and emptied.

In order to catch the clothes that drop down through the clothes chute, I may use a bag 21 supported over the bottom of the chute, as by clips 22, the bottom wall 5 of the chute being hinged so that it may be dropped, as illustrated by dotted lines in Figure 2, to permit the clothes to drop into the bag. With the bottom wall 5 raised, an opening is afforded between said bottom wall and the bottom of the dust chute to also permit removal of clothes.

In Figure 3 I have shown the construction extended to form chutes long enough to take in two floors. Where this is done the compartment for the shelves will be at the upper end of the construction above the second floor with openings and doors above each of the floors for permitting clothes to be dropped in from either floor and dust to be swept in from either floor. As it will be noted the construction shown in Figure 3 is similar to that in the other figures, except extended in length to take in two floors and with the added feature of a clothes cabinet 24 supported upon the lower end of the framework in the basement, and taking the place of the canvas bag shown in Figures 1 and 2. Where the clothes cabinet 24 is used, the same is formed with a door 25 to permit removal of the clothes from the cabinet.

As it will be apparent, by means of my improved features of construction I achieve a number of advantages over the ordinary constructions of clothes chutes: firstly, through the interior construction of clothes and dust passageways or chutes being enabled to drop clothes through the clothes chute, and from the same room permit the housewife sweeping into the dust chute all the floor dirt and dust.

The chutes are so constructed that no dust can get from the dust chute into the clothes chute to affect the clothes. The particular arrangement of dust and clothes chutes, as shown, permits a compartment at the top of the structure serving as a cupboard for the storage of articles on shelves, as well as the storing of long articles, as brooms.

The receptacle for the dust at the bottom of the dust chute keeps any falling dust from get-

ting into the clothes chute, and at the same time makes easier removal of the collected dust and dirt, and the dust inlet openings into the dust chute being at the floor level permit the easy 5 sweeping of all the dirt into the chute, eliminating the inconvenience of using dust pans, and the like.

I claim:

1. A combination clothes and dust chute of 10 the character described, comprising a boxing leading from a room downwardly into a basement, a vertical partition extending substantially from the floor level downwardly into the boxing and dividing the boxing into a clothes 15 chute and a dust chute, a horizontal wall closing the top of the dust partition, a door in the upper end of the dust chute at the floor level permitting dirt being swept into the dust chute, doors in the boxing above the top of the dust 20 chute permitting clothes being passed into the clothes chute, receptacles for clothes and dust at the bottom of the respective chutes, and a storage compartment at the upper end of said boxing above said chutes with the door of said 25 compartment constituting a combined closing door for said compartment and for the clothes chute.
2. A combination clothes and dust chute of 30 the character described, comprising a boxing adapted to be arranged between two rooms and leading downwardly to a room below a vertical partition dividing the lower end of said boxing into a clothes chute and a dust passage chute, an opening leading from the upper end of the 35 dust passage chute into an adjacent room at floor level, openings leading from adjacent rooms into the other chute some distance above floor level, a compartment in said boxing above said chutes, shelves in said compartment, the lower of said 40 shelves closing one end of said chutes, and a

fixed, horizontal wall closing the other chute at a point below said shelves.

3. A combination clothes and dust chute of 5 the character described, comprising a boxing adapted to be arranged between two rooms and leading downwardly to a room below a vertical partition dividing the lower end of said boxing into a clothes chute and a dust passage chute, an opening leading from the upper end of the 10 dust passage chute into an adjacent room at floor level, openings leading from adjacent rooms into the other chute some distance above floor level, a compartment in said boxing above said 15 chutes, shelves in said compartment, the lower of said shelves closing one end of said chutes, a fixed, horizontal wall closing the other chute at a point below said shelves, and a removable receptacle for the lower end of said dust 20 passage chute.

4. A combination clothes and dust chute of 25 the character described, comprising a boxing adapted to be arranged between two rooms and leading downwardly to a room below a vertical partition dividing the lower end of said boxing into a clothes chute and a dust passage chute, 30 an opening leading from the upper end of the dust passage chute into an adjacent room at floor level, openings leading from adjacent rooms into the other chute some distance above floor level, a compartment in said boxing above said 35 chutes, shelves in said compartment, the lower of said shelves closing one end of said chutes, a fixed, horizontal wall closing the other chute at a point below said shelves, a removable receptacle for the lower end of said dust passage chute, and a receptacle at the lower end of the other chute below said removable dust collecting receptacle.
